UNITED STATES PATENT OFFICE.

VAN VANDERBURGH, OF BACON HILL, ASSIGNOR TO HORATIO GRAVES, OF WARSAW, NEW YORK.

IMPROVEMENT IN AGITATORS FOR WASHING-MACHINES.

Specification forming part of Letters Patent No. 118,074, dated August 15, 1871.

To all whom it may concern:

Be it known that I, VAN VANDERBURGH, of Bacon Hill, in the county of Saratoga and State of New York, have invented a new and Improved Agitator for Washing-Machines; and I do hereby declare that the following is a full, clear, and exact description thereof, which will enable others skilled in the art to make and use the same, reference being had to the accompanying drawing forming part of this specification, in which—

Figure 1 represents a plan or top view of my improved agitator for washing-machines. Fig. 2 is a vertical section of the same taken on the plane of the line $x x$, Fig. 1.

Similar letters of reference indicate corresponding parts.

This invention relates to a new rotary agitator for washing-machines and wash-boilers, to be used for disturbing the suds and causing them to properly strike the articles to be cleaned. The invention consists chiefly in providing said rotary agitator with a projecting flange or rim and open loops, which produce currents in the water.

A in the drawing represents a circular disk or plate suspended from a shaft, B, to which it is rigidly or removably affixed in suitable manner, the shaft being suitably hung in the suds-box or boiler. The disk A is made of metal or other suitable material, and perforated, as shown at a in the drawing. Tubular ribs $b b$ are secured upon the surface of the disk A, radiating from

the shaft. These ribs are open at their outer ends and perforated at the sides, or open at their inner ends only, or at both ends, as may be found best for obtaining the proper currents of the liquid. From the edge of the disk A projects upwardly a rim or flange, c, which serves to retain the clothes on the disk and to prevent them from being caught between the edge of the disk and the suds-box. The flange c will also serve to keep the suds better agitated, as it prevents their rapid escape from the top of the disk. From the inner face of the flange c project loops $d d$, which are open at both ends to form counter-currents in the suds-box, and thereby aid in the operation of washing. The loops d are of suitable size, and four, more or less, of them may be employed.

I am aware that perforated rotary disks in washing-machines, combined with radial hollow and perforated arms, are not new to the public; and therefore I have no desire to claim these as part of my invention.

What I do claim, and desire to protect by Letters Patent, is—

In combination with perforated disk and perforated hollow arms, the upwardly-projecting rim c , arranged around the circumference of the disk, as and for the purpose specified.

VAN VANDERBURGH.
